Inventor

Henry C. Beggs

Watson E. Coleman

Attorney

Patented May 1, 1923.

UNITED STATES PATENT OFFICE.

HENRY C. BEGGS, OF FORT MORGAN, COLORADO.

HEAD GATE.

Application filed April 3, 1922. Serial No. 549,051.

To all whom it may concern:

Be it known that I, HENRY C. BEGGS, a citizen of the United States, residing at Fort Morgan, in the county of Morgan and State of Colorado, have invented certain new and useful Improvements in Head Gates, of which the following is a specification, reference being had to the accompanying drawings.

10 This invention relates to head gates, and more particularly to a head gate comprising a plurality of sections each separably shiftable to permit the passage of water through the head gate opening, and means for locking the sections either in the open or closed position.

15 A further object of the invention is to provide in a head gate a gate comprising a plurality of slidably connected sections each separably shiftable, the sections having a water tight joint with one another and with the head gate frame and being graduated as to size so that the flow of water may be adjusted to any desired volume.

20 25 A still further object of the invention is to provide a device of this character which is simple in construction and arrangement, readily installed, durable and efficient in service and a general improvement in the art.

30 35 These and other objects I attain by the construction and arrangement shown in the accompanying drawings wherein for the purpose of illustration is shown a preferred embodiment of my invention and wherein like reference characters designate like parts throughout.

In the drawings:

Figure 1 is a front elevation of a head gate constructed in accordance with my invention;

40 Figure 2 is a vertical sectional view taken therethrough on the line 2—2 of Figure 1; and

45 Figure 3 is a horizontal sectional view taken on the line 3—3 of Figure 1.

Referring now more particularly to the drawings, the numeral 10 indicates a frame preferably formed of angle iron in U shape, having the bight 11 of the U arranged 50 downwardly and the arms 12 thereof vertically directed. One flange of the angle iron is directed inwardly at the sides of the arm and the edges of the flange form a slideway for a gate 13. This gate comprises a plurality of sections 14 each having a tongue and groove engagement with the adjacent

sections 14, edge sections or those disposed adjacent the flanges of the arms of the U, being provided at their outer faces with rabbets 15 receiving the edge of the flange. The lower edge of each of the sections 14 is likewise rabbeted, as indicated at 16, and receives the vertically directed flange of the bight portion 11 of the U.

I preferably form the gate sections 14 by employing a plurality of thicknesses 17 of a desired material, the central thickness or thicknesses being offset to provide at one edge of the member 14 a tongue 18 and at the opposite edge thereof a groove 19 receiving the tongue of the adjacent section. In one of the outer sections the construction is necessarily modified to provide the groove or rabbet 15 for the reception of the flange of the associated arm 12.

Each section 14 has secured thereto a plurality of eyes 20, one row of these eyes preferably the uppermost, being aligned when the gate sections are all in the closed position. In the arms of the U aligned with the

eyes 20 of such upper row, I provide openings 21 through which a bar 22 may be directed. This bar is provided at one end with an operating handle 23 and at the opposite end which projects beyond the outer

face of the associated arm 12 with an opening 24 for the reception of a locking element 25 whereby the bar may be locked against withdrawal. This bar is passed through each of the eyes 20 of the uppermost row and locked to maintain the gate in closed position. When it is desired to permit the flow through the gate, any of the

sections 14 may be elevated until a desired eye of the member 20 is aligned with the openings 21 of the arms 12 and the bar 22 reinserted and locked in position, thus locking the gate in the open position. It will be readily seen that all of the sections 14

may be elevated if so desired, or any desired width of opening and height of opening with a given width may be obtained by merely locking the desired section 14, these sections being graduated as to size, and passing the bar 22 through the desired eye of the selected section. In order to prevent the

pressure of the water forcing the elevated gate sections outwardly by its pressure, guides 26 are secured upon opposite faces of the flange of the arms 12 and abut opposite faces of the sections 14 maintaining the same in position.

From the foregoing it is believed to be obvious that by a head gate constructed in accordance with my invention the maximum control of the flow through the gate is obtained and at the same time it is possible to lock the gate either in the closed position or in an adjusted position giving the desired degree of flow. It will furthermore be obvious that the construction as hereinbefore set forth is capable of some change and modification and is not necessarily limited to the specific employment hereinbefore set forth and I accordingly do not limit myself to such construction and arrangement as has been hereinbefore illustrated except as hereinafter claimed.

I claim:

1. A head gate comprising a frame, a gate 20
slidable in the frame and comprising a plurality of independently slidable sections, said sections being graduated as to size.
2. A head gate comprising a frame, a gate

slidable in the frame and comprising a plurality of independently slidable sections, means for locking the sections in closed or in 25 adjusted position, comprising a plurality of members carried by each of said sections and each provided with an opening, openings formed in the frame and with which the openings of the members of the sections are 30 alignable, a bar directed through the openings of the frame and adapted to be passed through the openings of the sections, and means for locking said bar against withdrawal from the frame. 35

3. In a head gate, a frame, a gate 40
slidable in the frame and comprising a plurality of sections each independently shiftable and having interlocking engagement with one another at their abutting edges, said sections being graduated as to size.

In testimony whereof I hereunto affix my signature.

HENRY C. BEGGS.
